FIG. 3.

INVENTOR
Carroll Knowles
BY Joseph P. Schopfield
ATTORNEY

UNITED STATES PATENT OFFICE.

CARROLL KNOWLES, OF HARTFORD, CONNECTICUT, ASSIGNOR TO PRATT & WHITNEY COMPANY, OF NEW YORK, N. Y., A CORPORATION OF NEW JERSEY.

TABLE-ACTUATING MECHANISM FOR MULTIPLE-CYLINDER-GRINDING MACHINES.

Application filed September 17, 1925. Serial No. 57,002.

This invention relates to cylindrical grinding machines for internal surfaces and in particular to a machine of this type adapted to simultaneously grind a plurality of bores in alignment. More particularly the invention relates to an internal surface grinding machine for grinding the cylindrical surfaces of a multiple cylinder internal combustion engine such as used in automobiles.

10 A principal object of the invention is to provide a work table actuating mechanism adapted to move the table supporting the cylinder block being ground bodily in a planetary path so that each of the aligned cylinders may be simultaneously ground to a high precision.

One feature which is advantageous is that I provide but one eccentric for actuating the work support in its planetary path and provide two superposed slides movable at right angles to each other so that the upper slide, on which the work to be ground is mounted, may be actuated in a planetary or bodily circular path while maintained always parallel to the line of grinding spindles.

Another primary object of the invention is therefore to provide actuating mechanism for the work supporting table which will have but one driving member in engagement with said table and which will be the only member to be adjusted to vary the movement of the table.

A further object of the invention is to provide a simple, effective and durable mechanism for actuating the work support for a multiple spindle cylindrical grinding machine permitting an automobile engine block to have all of its internal cylindrical surfaces ground simultaneously.

40 With these and other objects in view, my invention consists in the features of construction and operation set forth in the following specification and illustrated in the accompanying drawings.

45 In the accompanying drawings annexed hereto and forming a part of this specification, I have shown my invention embodied in a grinding machine for automobile engine cylinders but it will be understood that 50 the invention can be embodied in different forms of machines and that the drawings are not to be construed as defining or limiting the scope of the invention, the claims ap-

pended to this specification being relied upon for that purpose.

In the drawings: Figure 1 is a side elevation of a complete grinding machine, parts of the work support and actuating mechanism therefor being shown in section.

55 Fig. 2 is a plan view of the work supporting members, with the column and grinding spindles removed.

60 Fig. 3 is a fragmentary front elevation of the work supporting slides showing an engine block in position for operation.

65 In the above mentioned drawings, I have shown but one embodiment of the invention which is now deemed preferable, but it is to be understood that changes and modifications may be made within the scope of the appended claims without departing from the spirit of the invention.

Briefly, and in its broadest aspect, my invention comprises the following principal parts: First, a base; second, a work supporting table or platen movable in a horizontal plane upon an upper surface of the base; third, an intermediate slide disposed between the upper horizontal surface of the base and the lower surface of the work supporting table; fourth, interengaging guideways and projections disposed in pairs at right angles to each other so that the slides are constrained to move in directions normal to each other; fifth, actuating means comprising a unitary eccentric mechanism for bodily moving the upper or work supporting slide in a planetary path of different radii; sixth, a plurality of grinding wheels rotatably mounted, one for each of the cylinders to be ground; seventh, means to support, traverse and rotate these grinding wheels during the planetary movement of the supporting table.

85 Referring more in detail to the figures of the drawings, I provide a base 10 on which may be mounted a work supporting table 11. This table 11 is, in the embodiment illustrated, adapted to move about in a horizontal plane. Between this work supporting table 11 and the base 10 is an intermediate slide 12, the intermediate slide 12 being adapted to rest upon a horizontal surface of the base 10 and move forward and rearward on suitable guiding projections 13 therefor. The guiding projections 13 are

formed on the upper horizontal surface of the base 10, one in front and one in the rear. These projections 13 are engaged within guideways 14 formed in the lower 5 surface of the intermediate slide 12. On the upper surface of this intermediate slide 12 are horizontal guideways 15 engaged by projections 16 formed on the lower surface of the work supporting table 11 so that the 10 work supporting table 11 may move upon the intermediate slide 12 in a straight line. The guideways 14 and 15 are, as shown clearly in Figs. 2 and 3, disposed at right angles to each other so that the supporting 15 table 11 may be moved in any direction relative to the base 10 by means of its movement relative to the intermediate slide 12 and the movement of the intermediate slide 12 relative to the base 10. As shown in Fig. 20, the upper slide or table 11 and the forward portions of the intermediate slide 12 are extended toward the right and left and the guideways 15 and projections 16 on these members are provided near their extreme 25 ends. In this way the table 11 is accurately guided.

In order to actuate the work supporting table 11 in a planetary path so that the cylindrical surfaces of the parts being ground 30 may be simultaneously engaged with the grinding wheels 17, an eccentric 18 is mounted within the base 10 as shown clearly in Fig. 1. This, as shown, is disposed vertically and is of the compound type so that 35 the radius of movement of the eccentric projection 19 at its upper end may be widely varied. As the construction of this eccentric 18 and associated parts are or may be similar in every way to those shown and described in my copending application Serial 40 No. 16,343, filed March 18, 1925, it is not thought necessary to describe the mechanism in detail. It will be sufficient to state that by rotating the two worm wheels 20 and 21 45 shown in Fig. 2 simultaneously and at exactly the same speed, the eccentric can be rotated with its projection at a constant radii from its axis of rotation and that by relative rotation of the two worm wheels, preferably by a differential mechanism 22, the 50 radius of rotation of the eccentric projection 19 can be increased or decreased. As shown in Fig. 1, the intermediate slide 12 has an elongated opening through which 55 parts of the eccentric 18 and projection 19 may extend and the work supporting table 11 is provided with a bushing 23 forming a bearing closely fitting the eccentric projection 19. The eccentric movement applied 60 to this bushing 23 within the supporting table 11 actuates the work supporting table 11 in a planetary path by reason of the combined movement of the two slides 11 and 12. The intermediate slide 12 is constrained 65 by the guides 13 in the base 10 to move for-

ward or rearward, and the work supporting slide 11 is adapted to slide only in a direction toward the left or right by means of the guideways 15. The work supporting table 11 must therefore always assume parallel positions and as the eccentric projection 19 moves in a circular path of any diameter dependent upon the adjustment of the worm gears 20 and 21, the work supporting table 11 may move in a planetary path having the same radii. 75

The abrasive wheels 17 are, as shown in Fig. 1, supported at the lower ends of spindles 25 within individual heads 26 on a cross rail 27 adjustable vertically on a column 28. 80 As the means for supporting, adjusting and rotating the abrasive wheels 17 form no part of the present invention and may be similar to the means described in my copending application, no further description 85 is thought to be necessary.

What I claim is:

1. A grinding machine comprising in combination, a base, a column, a plurality of grinding spindles adjustably mounted thereon, a work support comprising a pair of inter-engaged slides movable in directions at right angles to each other, and means to actuate one of said slides whereby all points in said slide are rotated. 90

2. A grinding machine comprising in combination, a base, a column, a plurality of grinding spindles adjustably mounted thereon, a work support comprising a pair of inter-engaged slides movable in straight lines in directions at right angles to each other, and means to actuate one of said slides whereby all points in said slide are rotated. 100

3. A grinding machine comprising in combination, a base, a column, a plurality of grinding spindles adjustably mounted thereon, a work support comprising a pair of inter-engaged slides movable in directions at right angles to each other, and unitary means disposed centrally of said slide to actuate one of said slides whereby all points in said slide are rotated in a circle of different diameters. 105

4. A multiple spindle cylindrical grinding machine comprising in combination, a base, a column, a plurality of adjustably mounted spindles having abrasive wheels thereon mounted on said column, a work support on said base comprising a pair of superposed slides movable in directions at right angles to each other, and an eccentric adapted to actuate one of said slides. 115

5. A multiple spindle cylindrical grinding machine comprising in combination, a base, a column, a plurality of adjustably mounted spindles having abrasive wheels thereon mounted on said column, a work support on said base comprising a pair of superposed slides movable in directions at 120 125 130

- right angles to each other, an eccentric adapted to actuate one of said slides, and means to adjust the movement imparted to said slide by said eccentric during operation of said machine. 5
6. A multiple spindle cylindrical grinding machine comprising in combination, a base, a column, a plurality of adjustably mounted spindles having abrasive wheels thereon mounted on said column, a work support on said base comprising a pair of superposed slides movable in a horizontal plane in directions at right angles to each other, and an eccentric positioned centrally of one of said 10 slides adapted to actuate said slide engaged by said eccentric in a circular path.
7. A work support for multiple spindle cylindrical grinding machines comprising in combination, a base, a slide movable in a straight line thereon, a second slide movable on said first slide in a direction at right angles to the movement of said first slide, work supporting means on said second slide, and means engaging one of said slides at its mid- 15 portion to actuate all points in said second slide in a circular path.
8. A work support for multiple spindle cylindrical grinding machines comprising in combination, a base, a slide movable in a horizontal plane in a straight line thereon, a second slide movable on said first slide in a 20
